CLAIM

I claim the ornamental design for a basketball hoop lock, as shown and described.

DESCRIPTION

FIG. 1 is a perspective view of a basketball hoop lock of my new invention in its closed state locked onto a basketball rim;

FIG. 2 is a front elevational view of the basketball hoop lock of FIG. 1;

FIG. 3 is a left side elevational view of the basketball hoop lock of FIG. 1;

FIG. 4 is a rear elevational view of the basketball hoop lock of FIG. 1;

FIG. 5 is a top plan view of the basketball hoop lock of FIG. 1;

FIG. 6 is a right side elevational view of the basketball hoop lock of FIG. 1;

FIG. 7 is a bottom plan view of the basketball hoop lock of FIG. 1; and,

FIG. 8 is a perspective view of the basketball hoop lock of FIG. 1 in its open state prior to being locked onto the basketball rim.

The broken line environmental showing is for illustrative purposes only and forms no part of the claimed design.
